The ornamental design for a set of puzzle pieces for a ball puzzle, as shown and described.

DESCRIPTION

FIG. 1 is a perspective view of a hexagonal puzzle piece of a set of puzzle pieces for a ball puzzle, showing my new design;

FIG. 2 is a top plan view thereof;

FIG. 3 is a side elevational view thereof;

FIGS. 4 to 12 are top plan views of further hexagonal puzzle pieces;

FIGS. 13 to 16 are top plan views of pentagonal puzzle pieces; and,

FIGS. 17 to 19 are top plan views of pentagonal puzzle pieces; and,

FIG. 17 is a perspective view of the pentagonal puzzle piece, shown in FIG. 13.
